UNITED STATES PATENT OFFICE

WILLIAM F. COX, OF NEW YORK, N. Y.

DESIGN FOR A COMBINED CLOCK AND RADIO CASE

Application filed October 6, 1932. Serial No. 45,248. Term of patent 14 years.

To all whom it may concern:

Be it known that I, WILLIAM F. Cox, a citizen of the United States, residing at New York, in the county of New York and State of New York, have invented a new, original, and ornamental Design for a Combined Clock and Radio Case, of which the following is a specification, reference being had to the accompanying drawing, forming part thereof.

The figure is a perspective view of a combined clock and radio case showing my new design.

I claim:

The ornamental design for a combined clock and radio case as shown.

WILLIAM F. COX.
